UNITED STATES PATENT OFFICE

96,949

DESIGN FOR AN ASH TRAY OR SIMILAR ARTICLE

William Wieczorek, Battle Creek, Mich.

Application June 3, 1935, Serial No. 57,122

Term of patent 3½ years

To all whom it may concern:

Be it known that I, William Wieczorek, a citizen of the United States, residing at Battle Creek, in the county of Calhoun and State of Michigan, have invented a new, original, and ornamental Design for an Ash Tray or Similar Article, of which the following is a specification, reference being had to the accompanying drawing, forming part thereof.

I claim:

The ornamental design for an ash tray or similar article, as shown.

WILLIAM WIECZOREK.
